CLAIM

The ornamental design for an electrooptic display for a timepiece, as shown and described.

DESCRIPTION

FIG. 1 is a front elevational view of an electrooptic display for a timepiece showing my new design in a non-energized state;

FIG. 2 is a front elevational view thereof in an energized state showing a representative day/date of Wednesday the 14th, 10:09:36, and a chronograph time of 28:38;

FIG. 3 is a bottom plan view thereof, the top being a mirror image thereto;

FIG. 4 is a left side elevational view thereof, the right side being a mirror image thereto;

FIG. 5 is a rear elevational view thereof.

FIG. 1

FIG. 2

FIG. 3

FIG. 4

FIG. 5
